FUEL SUPPLY UNIT FOR OIL BURNERS

Herbert C. Osborne, Racine, Wis., assignor, by
mesne assignments, to Webster Electric Company,
Racine, Wis., a corporation of Delaware

Application January 2, 1937, Serial No. 118,794

1 Claim. (Cl. 103—126)

The present invention relates to fuel units for oil burners, and is particularly concerned with fuel units of the type which preferably include a liquid fuel pump, a strainer, and a pressure regulator unit.

One of the objects of the invention is the provision of an improved fuel unit of the class described, the mechanism of which is so arranged that with but few slight changes in construction and/or assembly the units may be arranged to meet all of the four requirements of the manufacturers of oil burners who use such units.

Assuming that the unit includes a pressure regulator, a strainer, and a pump, the burner might be located on the right hand side and the pressure regulator on the left hand side, or vice versa.

In each of these arrangements it might be required that the pump be arranged for right hand rotation or for left hand rotation. Therefore, the four possible requirements of customers with respect to the arrangement of the parts of the unit are that they may require right hand rotation, or left hand rotation, with either the strainer on the right or the strainer on the left.

Another object of the invention is the provision of an improved fuel unit for oil burners which may be embodied in a single stage pumping device or a double stage pumping device, and which may be utilized with a single pipe system or a return pipe system with reference to the excess of liquid fuel that is discharged by the pump.

Another object is the provision of an improved strainer unit, the parts of which are readily removable as soon as the cover has been removed so that they may be inspected, repaired, or replaced with a minimum amount of difficulty.

Another object is the provision of an improved pressure regulator unit which has its parts so arranged that they may be very quickly removed from the housing as soon as the cover is removed, thereby facilitating the inspection or repair, and reducing the amount of machine work involving fastening devices, to a minimum.

Another object is the provision of an improved pump unit having provision for preventing seal leakage around the shaft of the pump without interposing more than a minimum amount of friction to the rotation of the shaft, and having means for indicating a fuel leak through the seal, as distinguished from leakage of lubricating oil along the shaft.

Another object of the invention is the provision of an improved pump unit which is adapted to be taken apart with a minimum amount of labor,

the shaft being capable of immediate removal after its bearing plug has been removed for inspection or repair.

Another object of the invention is the provision of an improved fuel supply unit for oil burners, having a fuel pump, a strainer, and a pressure regulator, in which the parts of the pressure regulator and parts of the strainer are interchangeably adapted to be used in either of the housings provided with the pump.

Another object of the invention is the provision of an improved fuel unit for oil burners, in which all the connections for an installation are located at the bottom, for greater convenience.

Another object of the invention is the provision of an improved fuel unit for oil burners, which is provided with an oil reservoir surrounding the gear pump, and with means for restricting the intake passage of the pump, both for the purpose of silencing the noise involved in the operation of the gear pump. The restriction on the intake passage of the gear pump tends to volatilize the lighter parts of the liquid fuel, which cushions the action of the gear teeth and reduces noise.

Another object of the invention is the provision of an improved pump structure, the parts of the pump being built up of a series of separate steel plates by means of which these parts may be more accurately machined and produced in large volume, at a lower cost, and constructed in such manner that the pump is adapted to operate for longer periods of time without likelihood of leakage, or change of dimensions due to wear, and by means of which the pump may be arranged either for right hand or left hand rotation, or for use with the strainer on the left hand or the right hand.

Other objects and advantages of the invention will be apparent from the following description and the accompanying drawings, in which similar characters of reference indicate similar parts throughout the several views.

Referring to the four sheets of drawings,

Fig. 1 is a front elevational view of a two stage fuel supply unit constructed according to the present invention, the front side being that opposite to the projecting drive shaft;

Fig. 2 is a vertical sectional view, taken on the plane of the line 2—2 of Fig. 3, looking in the direction of the arrows, showing the details of construction of the strainer unit and pressure regulator unit and their association with the other parts of the housing;

Fig. 3 is a vertical sectional view, taken through

the two stage pump unit on the plane of the line 3-3 of Fig. 1, looking in the direction of the arrows, showing the details of construction of the pump and its shaft sealing device. This view illustrates the arrangement of the parts of the pump when it is arranged for right hand rotation with the strainer on the left and the valve on the right hand side. The gear arrangement is the same for left hand rotation when the valve is placed on the left and the strainer is located on the right hand side.

Fig. 4 is a fragmentary, vertical sectional view, taken on the plane of the line 4-4 of Fig. 3, showing details of construction of the pump mechanism, and in particular the bearing plate; 15

Fig. 5 is a fragmentary sectional view, taken on the plane of the line 5-5 of Fig. 3, looking in the direction of the arrows, showing the opposite side of the pump bearing plate and other details;

Fig. 6 is a vertical, sectional view, taken on the plane of the line 6-6 of Fig. 3, showing the fuel unit casting, which may be interchangeably used to provide a pump for right hand rotation or left hand rotation, the figure particularly showing the part of the housing to which the pump mechanism is attached; 20

Fig. 7 is a fragmentary sectional view, taken on the plane of the line 7-7 of Fig. 6, looking in the direction of the arrows, showing the silencer plug for restricting the intake passage of the pump to reduce noise in the operation of the pump;

Fig. 8 is a vertical sectional view, similar to Fig. 3, but showing the position of the parts of the pump mechanism when the pump is arranged for left hand rotation with the strainer on the left and the valve on the right, or for right hand rotation with the valve on the left and the strainer on the right; 35

Fig. 9 is a vertical sectional view, taken on the plane of the line 9-9 of Fig. 8, looking in the direction of the arrows, showing the arrangement of the parts of the pump, and in particular an elevational view of the bearing plate in a different position from that of Fig. 4;

Fig. 10 is a vertical sectional view, taken on a plane similar to that of Fig. 3, of a modification embodying the invention in a single stage pump unit, but utilizing the same type of base casting as is used in the embodiments of Figs. 1-9; 50

Fig. 11 is a vertical, sectional view, taken on the plane of the line 11-11 of Fig. 10, looking in the direction of the arrows, showing the details of construction of the single stage pump of Fig. 55 10, and in particular an elevational view of the gear plate;

Fig. 12 is a bottom plan view of a strainer partition plug;

Fig. 13 is a top plan view of the strainer partition plug; 60

Fig. 14 is a view in perspective of the strainer partition spring;

Fig. 15 is a view in perspective of a valve partition holding spring;

Fig. 16 is a fragmentary, vertical sectional view, taken on the plane of the line 16-16 of Fig. 3, looking in the direction of the arrows, showing plate 161 in elevation;

Fig. 17 is a fragmentary, vertical sectional view, 70 showing the course of the output conduit from the high pressure gears 183, 184 to the valve chamber 185;

Fig. 18 is a fragmentary, sectional view of a housing for a single stage pump unit, the gears 75 being shown in dotted lines, to show the arrange-

ment of conduits for one form of that unit, adapted for rotation of the drive shaft in a clockwise direction, and having the strainer arranged on the right and the regulator valve on the left, as shown in the figure. 5

Fig. 19 is a similar view, showing the arrangement of conduits for the same type of unit, when the drive shaft is arranged for counterclockwise rotation, with the strainer on the right and the regulator valve on the left; 10

Figs. 20-23 are fragmentary, horizontal sectional views, taken on the planes bearing similar numbers in Figs. 11, 17, 18 and 19, looking in the direction of the arrows, showing the arrangement of the conduits, extending from the strainer chambers and pressure regulator valve chambers to the pump gears in each of these modifications. 15

Referring to Figs. 1 to 3, the present fuel unit for oil burners preferably comprises a fuel pump, indicated in its entirety by the numeral 20 (Fig. 20 3), a strainer unit 21, and a regulator valve unit 22.

In order to accomplish the objects referred to above, the fuel unit may be provided with a base casting 23 (Fig. 3), to which the pump unit 20 is 25 attached, and which has a pair of housings 24, 25, the latter preferably similar in shape, so that the housings may be used interchangeably for housing the strainer unit 21 or the pressure regulator unit 22. In order to make provision for 30 use of the fuel unit with a one pipe system or a two pipe system, the base casting 23 is preferably provided with an internal chamber or conduit 26 adapted to communicate either with the strainer unit or the pressure regulator unit, and also in 35 communication with the pump, as will be described later herein.

The conduit 26 is preferably located between the housings 24, 25, and may be provided at its lower end with a threaded aperture, forming a 40 by-pass outlet 27, which may be closed by a closure or threaded plug 28, or used with a suitable pipe leading back to the tank of liquid fuel.

The housings 24, 25 are preferably substantially cylindrical in shape, except where they 45 merge into the main body of the base casting 23, and at the top, which is provided with a substantially rectangular formation 29, and with enlargements 30 at its corners, providing sufficient body so that when apertures are drilled and 50 tapped for the screw bolts 31, the strength of the material will be adequate.

The rectangular open end portions 29 of the housings 24, 25 are provided with the flat machined and ground seating surfaces 32, 33, adapted to be engaged by the flat lower face portion 33 of either cover 34, so that the cover has a fluid-tight fit with the housing 24 or 25 when the screws 31, passing through the cover, are driven home into the housing 24 or 25. A suitable 60 gasket 35 is preferably interposed between the seating surfaces 32 and 33.

The cover 35, used for a housing when it encloses the pressure regulator, is similar in shape, so that either cover 34 or 35 will fit on either 65 housing, but the cover 35 has an inwardly projecting, cylindrical lug 36, formed with a reduced cylindrical portion 37 and an annular seat 38. The heavy helical spring 39 fits about the reduced portion 37 and against the seat 38. The cylindrical body 36 has a threaded bore 40 for receiving a headless adjustment screw 41, and the upper end of the bore may be closed by a short screw bolt 42.

The flat seating surface 33 on the cover 34 ex- 75

tends over the inner edge of the housing wall 24, providing an annular seat 43, against which the helical spring 44 engages. Each of the housings 24, 25 is provided at its lower end with an enlarged, tapped bore 45 of the same thread and size for receiving a threaded plug. The threaded plug 46, which is used for the housing when it is a strainer housing, comprises a threaded member having a cylindrical portion threaded complementarily to the bore 45, and having an external, non-circular portion 47.

It is provided with a centrally located bore 48 and counterbore 49, the former being provided with a pipe thread. The opening 48, 49 in plug 46 may be used as the inlet to the fuel unit, being connected with a pipe 50, leading from the liquid fuel in a tank. It may also be used as a clean-out opening by removing the pipe.

When either housing is used for the pressure regulator, it is provided with a cylindrical body 51, the lower portion of which is similar in shape to the plug 46; that is, it has an enlarged, non-circular formation 47, the bore 48, and the counterbore 49.

The tapped bore 48, however, is then adapted to receive a threaded fitting 52 for connecting a pipe 53, which leads to the burner nozzle, or other device used for a burner.

Each of the housings 24 and 25 is provided with a cylindrical wall, forming a substantially cylindrical chamber 54, but the chamber 54 is separated from an upper bore or chamber 55 by an annular shoulder 56. The bores 54, 55, 56 indicate the parts of the pressure regulator chamber at the right of Fig. 2, and the corresponding similar parts of the strainer chamber at the left will be indicated by the numerals 54a and 55a, for convenience in describing the course of the liquid fuel.

The annular rib 56 is provided with a machined seating surface 57, in each case, and the sizes of the bores 55, 55a are identical, so that the strainer or pressure regulator will fit in either chamber 54, 54a.

The chambers 55, 55a are each provided with an inwardly extending diagonal conduit 58, 59 on the side toward the upper end of conduit 26. The upper end of conduit 26 terminates in a pair of diagonally extending walls 60, 61, each of which is provided with a threaded bore 62, 63, adapted to be closed by a small screw plug 64 provided with a kerf.

Due to the diagonal arrangement of the walls 60, 61, the screw plug 64 is accessible through the top openings of the housings 24, 25, and may be removed or inserted at will. The purpose of the plug 64 will be described in detail in the operation of the device.

Referring now to the strainer unit 21 at the left of Fig. 2, this unit is preferably mounted on a partition plug 65, which may comprise a substantially cylindrical member fitting in the machined bore 55a and provided with a lower flat machined seating surface 66.

The partition plug 65 may comprise a member made of die cast metal, having on its lower surface a plurality of annular, downwardly projecting ribs 67, 68 of substantially rectangular cross section. These ribs are spaced from each other sufficiently to receive between them the strainer members at suitable spacing, and the outermost rib 67 is spaced from the edge of rib 56 in body 24 or 25, to permit a strainer member to be located outside the rib 67.

Each of the ribs 67, 68 is provided with a plurality of apertures or slots 69, 70, passing

through the partition plug 65 into the chamber 55a. These slots 69 and 70 in the case of a die cast metal plug 65 are ... slots at the lower edges of the ribs 67, 68, but may be suitably enlarged at their upper ends, and portions of the ribs 67, 68 may be cut away at the slots 69, 70, as shown in Fig. 12.

The partition plug 65 is also provided with a centrally located threaded bore 71 for receiving the threaded end 72 of a rod 73, which holds the strainer unit 21 together. The upwardly projecting end 72 of the strainer rod 73 serves as a handle for lifting the strainer unit out of its housing 24. The partition plug 65 is held in place against the seating surface 66 by the helical spring 44, which is of greater normal untensioned length than shown in Fig. 2, so that when the cover 34 is secured in place by screw bolts 31, the spring 44 is placed under pressure, and by engagement with the seating surface 43 on cover 34 it presses and holds the partition plug 65 into the position of Fig. 2. In order to provide the substantially equal spring pressure on all parts of the partition plug 65, the engaging end portions 74, 75 of the spring 44 are flattened out and the end coil is brought into the same plane as shown in Fig. 14. The lower end coil 80 engages about an upwardly projecting cylindrical portion 81 on the partition plug 65.

The strainer unit 21 preferably comprises a plurality of strainer members 76, 77, 78, 79. These strainer members are preferably substantially cylindrical in form and of successively smaller diameter, preferably differing by substantially equal increments of diameter.

The strainer elements 76-79 may be identical in construction except for the difference in size, and each may consist of a tube of fine wire screen formed out of a sheet of screen which is bent to cylindrical form, and its edges overlap and are secured together by solder. Each of the upper and lower borders of the screen elements 76-79 may be suitably reinforced and provided with a solid imperforate portion 82, by dipping the end of each screen element in solder to a depth of about a quarter of an inch, as shown in Fig. 2. Where the screen elements are quite close together and show a tendency to collapse, they may be separated by a spacing member, such as, for example, the spacer 83, which comprises a helical wire spring having its coils located between the strainer elements 77, 78.

Since the depending ribs 67, 68 on the strainer partition plug 65 are of rectangular section, they have cylindrical inner and outer wall surfaces for engaging the reinforced end portions 82 of the strainer elements 76-79. The inner strainer 79 has its upper end fitting against the inner cylindrical wall of depending rib 68. The next strainer element 78 fits against the outer cylindrical wall of depending rib 68. The coil spring 83 fits loosely between the strainer elements 77, 78. The strainer element 77 fits against the inner cylindrical wall of depending rib 67, and the strainer element 76 embraces the outer cylindrical wall of depending rib 67.

In a similar manner the lower ends of the strainer elements 76-79 (which are all of the same length) fit against the cylindrical surfaces of upwardly extending ribs 84, 85, carried by the end closure 86 of the strainer element 21.

This end closure plate, as distinguished from the partition plug 65, has through apertures 87, 88 located between the ribs 84, 85 and inside the rib 85, whereas in the partition plug the aper-

tures are located at and through the ribs. The upper edges of the ribs 84, 85 may be tapered for convenient insertion between the screen elements.

5 Like the partition plug 65, the apertures 87, 88 in the end plate 86 may be elongated so that fewer apertures are necessary. End plate 86 is also provided with a centrally located bore 89 for passing the threaded end 90 of the strainer rod 73, which has a knurled thumb nut 91.

When the strainer elements 76-79 are assembled between the partition plug 65 and end plate 86, as shown, with the rod 73 passing therethrough and secured at its upper end by being 15 threaded into the bore 71, the strainer elements may be clamped in place by means of the nut 91.

The strainer unit 21 is then inserted in the strainer chamber, which comprises either the housing 24 or 25, and secured in place by means 20 of the cover 34 engaging spring 44. The securement of the cover secures the strainer unit in place, and as soon as the cover is removed for access to the strainer, the strainer unit may be easily removed by merely lifting it out by means 25 of the handle 12.

Each of the housings 24 or 25 may be provided with a laterally located boss 92, which has a bore communicating with chamber 54 or 54a, provided with a pipe thread for receiving a pipe 30 93 or 94. These pipes may be used for connection to a vacuum gauge in the case of the strainer housing 24, or for connection with a pressure gauge in the case of the regulator valve housing 25. Either of the pipes 93, 94 may be replaced 35 with a vent plug where no gauges are used.

The partition plug 65 divides the strainer housing into two chambers, and the liquid must pass through the strainer elements before getting from one chamber to the other, as follows:

40 Liquid fuel is taken in at the port 49 at the bottom of the strainer unit, and due to the suction of the pump it is drawn in at the apertures 87, 88 of the strainer unit. It also surrounds the strainer unit so that the liquid fuel passes 45 through the strainer elements, as shown by the arrows at the middle of Fig. 2. Thus it passes into the spaces between the strainer elements 76, 77 between the strainer elements 78, 79, and thence through apertures 69 and 70 in the partition plug 65, to the chamber 55a.

Referring to the right hand portion of Fig. 2, the plug 51 may be provided with a cylindrical extension and with a through aperture 95 communicating with an enlarged bore 96. Plug 51 55 may be constructed of steel and provided with a bronze or brass valve seat plug 97. The valve seat plug 97 comprises a substantially cylindrical member, the lower end of which has a tight frictional fit in the enlarged bore 96 so that the 60 seat plug 97 projects from the bore.

Valve seat plug 97 is provided with a through bore 98, which may be of the same size as the bore 95, and communicates therewith. At its upper end the edge 99 of this bore constitutes a 65 valve seat for engagement with the conical end 100 of a needle valve member 101. That portion of the valve seat plug 97 which projects out of the plug 51 may be used to support a tubular member 102, which constitutes a cylinder for a 70 piston valve member 103.

Cylinder 102 may have a tight frictional fit on the valve seat plug 97 so that it is in fixed position with respect to the plug 51. Cylinder 102 is provided with a plurality of through apertures 75 104, preferably located at equally spaced points

about its periphery and just above the valve seat 99, so that the apertures 104 provide communication between the chamber 54 and the space 105 in cylinder 102.

The regulator valve unit 22 is preferably provided with a pressure responsive means comprising a flexible bellows member 106. The bellows 106 may have its upper end initially provided with a substantially cylindrical flange like the flange 107 at the bottom. This initially cylindrical flange is passed through an aperture 108 in a cupped partition plate 109, which is of sufficient size to fit in the chamber 55 or 55a. The flange referred to may then be spun over, as at 110, and secured in the cup formation 111 by a 15 layer of solder, which also provides a liquid-tight joint between the bellows and partition plate 109.

The partition plate 109 may be engaged by a galvanized steel washer 112, which also has a 20 sliding fit in the bore 55, and has an aperture 113 for passing the bellows spring 114. The coil spring 39, previously referred to, is a very heavy holding spring, such as, for example, a 400 pound spring. As shown, it is rectangular in cross section and comprises a plurality of coils, the upper and lower coils of which are tapered so that the spring 39 presents flat ends for engagement with the seating surface 38 and with the washer 112. This assures substantially uniform force applied 25 to the washer 112 and to the bellows plate 109 on all sides. The force exerted by the spring 39 must be sufficient to resist any pressure which might be placed upon the complete bellows 106 and piston 103 carried thereby, under ordinary 30 operating conditions, so that the partition plate 109 will always be held in fixed position.

The arrangement of the spring 39 and partition 40 112 has the additional advantage of providing an auxiliary relief valve action for emergencies.

Referring to Fig. 2, it will be observed that the partition 109 need only be lifted off its seat high enough to destroy the effect of the seal of the gasket 109a to permit liquid to flow around the 45 partition by pressing the spring 39. A lift of a few thousandths would be sufficient to destroy the seal and relieve the pressure. In case the piston by-pass valve sticks, excessive pressure in the chamber 54 would force the partition 112 50 upward and be relieved through the port 63.

The spring 39, like the spring 44, is normally slightly longer than the space into which it is compressed in Fig. 2, so that the cover 35 may be applied and the screws 31 started without 55 exerting force on the spring 39; but thereafter, when the screws 31 are driven home, a screw driver must be used, and the spring 39 is placed under a heavy pressure, referred to above.

Like the strainer unit 21, the regulator valve 60 unit 22 may be quickly taken apart by merely removing the cover 35, which releases the spring 39 and all other parts, so that the bellows 106 and piston 103 may be removed for inspection. No other securing devices are needed, and therefore the machining of parts incident to other securing devices is eliminated.

The lower end of the bellows 106 has its cylindrical flange 107 engaged about the cylindrical surface of a radially projecting flange 115 carried by a supporting plug 116. The supporting plug 116 may be constructed of brass, and it has an upwardly projecting annular flange 117 surrounding a bore 118, which provides a socket for the lower end of bellows spring 114.

The flange 115 abuts against the lowermost inwardly extending fold of the bellows 106, and the flanges 107 and 115 are soldered together to provide a fluid-tight joint. The plug 116 has 5 an outer cylindrical surface which is a tight frictional fit in the cylindrical bore 119 of the steel piston 103, the end of which abuts against the flange 115.

The piston 103 is further secured on the plug 10 116 by the fact that a by-pass port 120 is bored through the piston 103 and into the plug 116 after these parts are fastened together. An axially extending bore 121 in the plug 116 communicates with the by-pass port 120. The upper, 15 inner corner 122 of the cylinder 102 provides the cut-off edge of the piston and cylinder valve.

In order to provide the piston 103 with a definite cut-off edge, the piston 103 is provided with a flattened portion 123 extending across the end 20 of the aperture 120, and the flat shoulders at the end of this flat portion 123 have corners, the upper one of which constitutes a cut-off edge for the cylinder and piston valve.

It will be seen that the chamber 54 communicates with the chamber 55 through the aperture 120, aperture 121, bellows 106, and aperture 113, and this communication may be cut off by the 25 cut-off corner 122 on cylinder 102 cooperating with the piston 103.

The piston 103 is also preferably provided with a leakage slot 124 which extends from the recess provided by the flattened portion 123 down to the lower end of the piston, parallel to the axis of the piston. This leakage slot is adapted to provide leakage from the chamber 54, by means of 30 apertures 104, space 105 leading to slot 124, and thence to aperture 120, whenever the piston is in the position of Fig. 2, with the needle valve leading to the burner port 49 closed. When the 35 regulator valve is closed, the pressure in the chamber 54 is relieved through the leakage port 124 leading to the chamber 55, and eventually back either to the inlet of the pump or to the by-pass port 27.

The amount of leakage permitted by the slot 124 is not sufficient, however, to effect the operation of the bellows 106, which moves responsively to the pressure in the chamber 54. The cylinder 103 has its bore 119 extending beyond the plug 40 116 and communicating with a smaller bore 125 centrally located in the lower end of the piston.

Between the bores 119 and 125 there is a partially spherical surface 126 adapted to engage the ball 127, which is carried by the upper end 45 of the stem of needle valve 101. The stem projects through the aperture 125, with which it has a suitable clearance, and the upper end of the ball 127 engages the end 128 of plug 116, there being sufficient clearance about the ball 50 127 to provide a limited universal movement.

Thus the conical end 100 of the needle valve 101 is adapted to find its own proper position with respect to the circular seat 99, thereby assuring a perfect closure of the needle valve at 55 all times. The piston 103 is acted upon by the spring 114, which engages in the socket 118 of plug 116 at its lower end. The upper end of the spring 114 is engaged in a cup shaped member 70 128, which has its depending flange embracing the spring, and has a partially spherical depression 129 for engaging the complementary end of screw 41. The cup shaped member 128 may have its depending flange slotted so that even though it is screwed down into engagement with the

washer 112, the liquid fuel has egress from the bellows 106, through the slots of the cup.

The operation of the pressure regulator is as follows: Liquid fuel under pressure is supplied to the chamber 54 when the pump is started and 5 when the pressure of liquid fuel arrives at a predetermined pressure suitable for operation of the burner, this pressure acting on the bellows 106 and piston 103, to which it has access, from the chamber 54, moves the piston and lower end 10 of the bellows upward in Fig. 2, carrying with it the needle valve 101. The needle valve 101 then opens the burner port at the seat 99, and liquid fuel is supplied to the burner. As the pressure continues to rise in the chamber 54, for the 15 reason that the pump is adapted to supply an excess of fuel over that required for the burner, the piston 103 moves up until the cut-off edge 122 places the aperture 120 in communication with the chamber 54.

An amount of liquid fuel is by-passed through the apertures 122, 121 and bellows 106, back to the chamber 55, to the by-pass port 27 or to the inlet of the pump, depending upon the opening 20 of the piston valve at 122.

The piston valve continues to open a sufficient amount to by-pass this excess oil and thereby maintains the pressure substantially constant in the chamber 54 within predetermined limits. The leakage that occurs through the leakage slot 124 during this time does not materially affect the operation of the valve, but when the pump is shut down and ceases to generate pressure, the pressure drops in the chamber 54, the bellows 106 elongates, moving the piston 103 35 downward, and closing the by-pass port 120. Thereafter the needle valve 101 closes the burner port at seat 99, and the continuing leakage through the slot 124 reduces the pressure in the chamber 54 to atmospheric, permitting a more 40 positive seating of the needle valve 101, since there is no longer any pressure exerted on the bellows 106 except that of the spring 114.

The pressure at which the needle valve will open may be suitably adjusted by the pressure 45 on the spring 114, which is adjusted by means of the screw 41. The spring 114, like the springs 44 and 39, has the endmost coil at its upper end disposed in the same plane. The same is true at the lower end, so that the spring exerts 50 a substantially axial force on the piston 103 and does not tend to bind the piston in its cylinder 102, as might be the case if the spring engaged only at one side.

The base casting 23 (Fig. 3) is provided (Fig. 6) with a machined face 131 of sufficient size to support the pump mechanism and the reservoir housing 132, which is adapted to enclose the pump and to permit it to be enveloped by a supply of liquid fuel.

The reservoir housing 132 comprises a cast metal member of oval cup shape, having one open end and having its closed end provided with a face 133, which may be used for the name plate 134, which is secured thereto by headed 65 pins 135, driven into apertures.

The outer wall 136 of the reservoir housing 132 is suitably thickened at a plurality of equally spaced points to provide sufficient material so that apertures may be bored in the wall 136 of 70 the housing for the screw bolts 137 without communicating with the reservoir space 138.

The screw bolts 137 pass through the apertures in the reservoir housing 132 and through a suitable gasket 139, and are threaded into 75

threaded bores located in the face 131 of the main casting 23. The edge 140 of the housing wall 136 is machined to provide a fluid-tight engagement with the face 131 when the screw bolts 137 are driven home, clamping the gasket 139.

Referring to Figs. 6 and 7, each of the upper chambers 55 and 55a is in communication with a port 141, 142, respectively, each port being located in the face 131 of the main casting 23. The port 141 communicates with the bore 143, which leads to a cored and milled recess 144, located in the side of upper strainer chamber 55a.

The port 142 communicates by means of aperture 145 with a similar recess 146 located in the upper pressure regulator chamber 55. Each of the bores 143, 145 is provided with a threaded portion 147 at its upper end for receiving a threaded restriction sleeve or plug 148, having a kerf 149 for receiving a screw driver. This restriction plug is placed in the conduit 143 leading from the strainer chamber, but since both the bores 143, 145 are of the same size, the plug will fit either conduit, and the strainer 25 may be located on the left hand or the right hand side of the unit. The restriction plug places a predetermined restriction in the intake side of the pump, which puts a vacuum on the pump and tends to volatilize the liquid fuel. The 30 volatilized fuel has a cushioning action between the gears of the pump, thereby silencing the pump.

The wall 151 between the by-pass conduit 26 and the face 131 is provided with a circular bore 152 provided with a slot 153 extending from the face 131 to the by-pass conduit 26. This slot provides lubricating means for the pump shaft. It always is on the side of the bearing toward the idler shaft, because in this position 40 the liquid pressure forces the gears, and hence the shafts, apart, thus leaving space between the shaft and the bore 152 for the entrance of pumpage which serves as the lubricant.

The bore 152 serves as a bearing for the pump shaft 156. The wall 151 is provided with a pair of additional bores 157 and 158, each of which is adapted to receive a pin 159 or a tube 160.

The bores 157, 158 communicate with the by-pass conduit 26, and are to be used interchangeably with the solid pin 159 or sleeve 160, both of which perform the function of lining up and supporting a plurality of steel plates 161, 162, 163, 164, which form the pump housing. The sleeve 160 performs the additional function of placing the reservoir space 138 in communication with the by-pass conduit 26, and it will be apparent that this communication may be had with the parts arranged as shown in Fig. 3, or with the parts arranged as shown in Fig. 8. Here the same sleeve 160 is again arranged near the top of the plates for the reason that it is desired to keep the reservoir full of liquid fuel up to the sleeve and above the intake ports to the gears of the pressure stage. This makes the pump self-priming.

The face 131 is also provided with a plurality of threaded bores 165, 166, 167, 168 (Fig. 6) for receiving a plurality of screw bolts 169 which pass through the plates 161-164 and are threaded into the bores 165-168. In the embodiment of Fig. 9, two of these bores 165, 166 are located in the lower part of the face 131 in position to line up with the same apertures in the plates 161-164, which are arranged in the lowered position.

The face 131 is also provided with the ports 170, 171 (Fig. 6), which communicate by means of the conduits 172, 173 with the lower chambers 54a and 54 respectively, comprising the lower strainer chamber and lower pressure regulator 5 chamber. These conduits 172, 173 serve as inlet ports for these chambers, whichever chamber is used as a regulator valve chamber.

In the embodiment of Fig. 2, the conduit 173 is the effective one, whereas the conduit 172 is 10 closed.

Plate 161 is provided with apertures 174, 175, which are adapted to register with the ports 170, 171, respectively. Plate 161 is also provided with apertures 176, 177, 178, 179, adapted to 15 cooperate with slots in the plate 162 to form conduits under certain conditions. The plate 161 is also formed with the two laterally inter-communicating gear bores 181, 182, which are adapted to engage the machined edges of the 20 gear teeth of gears 154, 155, providing a close sliding contact.

The gears 154 and 155, as well as the high pressure gears 183, 184, are all preferably of the helical type, for the purpose of reducing noise, 25 and the direction of helix is so arranged with respect to rotation that helical teeth force the liquid sidewise toward the discharge ports of the pump, and are all provided with flat side faces adapted to have a closely fitting sliding contact 30 with the adjacent walls of the plates 161, 162, 163 or 164.

The tips 185 of all of the gear teeth are preferably provided with a surface which appears to be slightly flattened, but which is actually partially cylindrical and has sliding contact with the peripheries of the gear-receiving bores, such as the bores 181, 182.

The plate 161 is also provided with the apertures 186, 187, located at the top and bottom 40 thereof, in Fig. 16, for receiving the sleeve 160 and pin 159. Similar apertures 186, 187, to which the same numerals have been applied, are present in the plates 162 and 163.

Referring to Figs. 3 and 5, the pump partition plate 162 is of similar shape, and it is provided with the cylindrical bores 188, 189 for receiving the stub shaft 190 and the drive shaft 156. These cylindrical bores serve as bearings for those shafts which have a close rotating fit in 50 the bores.

In addition to these bores, the plate 162 has registering apertures for the screw bolts 169, which secure all of these plates together, and to the main casting 23; that is, plates 161, 162, 163 55 and 164 have apertures which register with the threaded bores 165-168 (Fig. 6) in the main casting 23.

The plate 162 (Fig. 5) is provided with the apertures 191, 192, the former being located to 60 register with the aperture 175 in plate 161 when the pump is assembled as shown in Figs. 3 and 5. When the plate 162 is inverted, the lower aperture 192 will appear in the right upper quarter of the plate, referring to Fig. 5, and would register with the aperture 174 in the plate 161 for a different assembly and different use of the unit.

The plate 162 is also provided with the transversely extending rectangular slot 193 which extends from the left side of Fig. 5 to a point located at the right of the point of engagement of the gears 154, 155. This is the output conduit from the gear pump, comprising the gears 154, 155, leading into the reservoir 138.

Plate 162 is also provided with a transversely

extending rectangular slot 194, which leads from a point slightly spaced from the end of slot 193, that point being located immediately at the right of the point of engagement of the gears, and 5 communicating with the spaces between the teeth at the ends of the teeth.

Slot 194 comprises an intake conduit for the gear pump, consisting of gears 154, 155. This slot communicates with a transversely extending slot portion 195 at the end, and located at such 10 a distance from the boundary of the plate that the transversely extending slot 195 will have its upper and lower ends in registry with the apertures 177, 179 of plate 161 (Fig. 16).

15 When the plate 162 of Fig. 5 is inverted so that the slot 195 is at the left (Fig. 5) and the slot 193 at the right, then the upwardly and downwardly extending slot 195 will have its end portions in registry with the apertures 176, 178 20 of the plate 161. That condition would be for a reverse rotation of the pump from that which would be necessary for the installation of Fig. 3.

Referring now to Fig. 5, the inlet for pump gears 154, 155 may be traced as follows: Slot 194, lower 25 leg of slot 195, aperture 179 (Fig. 16), aperture 141 (Fig. 6), conduit 143, restriction 148, to upper strainer chamber 55a.

The outlet from this stage of the gear pump leads from slot 193 to the edge of the plate assembly into reservoir 138 surrounding the pump. 30 The aperture 177 in the plate 161 and the upper leg of slot 195 are closed because they come against the flat face 131 of the main casting 23 at a point where there is no hole in this mode of assembly.

35 The plate 162 has upon its opposite side, which is shown in Fig. 4, certain additional slots. The apertures 191 and 192 communicate with a vertically extending slot 196 in plate 162 upon the left face thereof (Fig. 3). Vertical slot 196 40 communicates with a horizontal slot 197 which leads to a point 198 at the right of the point of contact of gears 183, 184 (Fig. 4), which is the output side of the gears.

45 Plate 162 has on this face also a transversely extending slot 199 which leads to the outer edge of the plate from the intake side of gears 183, 184. Slot 199 communicates at its left end with the reservoir 138 and is the intake conduit for the high pressure stage 183, 184 of the pump.

50 The next plate 163 of the pump assembly (Fig. 3) is similar in shape to the plate 161, being provided with the apertures 186, 187 for aligning studs 159, 160, and being provided with the bolt hole apertures 165-168 for the screw bolts 169. This plate is also provided with the gear apertures 200, 201, similar in shape and size to the gear apertures 181, 182 of Fig. 16. The plate does not have any other apertures, and it serves 55 as a housing for the toothed edges of gears 183, 184.

60 The cover plate 164 is provided with the same bolt apertures 167-168 for the screw bolts 169, the heads of the bolts being preferably countersunk in the plate 164. This plate provides a closure for the end of the pump mechanism, but is also provided with an aperture 202 registering with the aperture 203 in the sleeve 160 at the top of Fig. 3 to place the reservoir 138 in communication with the by-pass conduit 26.

65 Referring now to Fig. 4, the output from the high pressure gears 183, 184 is at the point 198 into the slot 197. The course of the liquid fuel from the high pressure side of the pump may be traced as follows: Conduit 197, slot 196, aperture 191 (Fig. 4), aperture 175 (Fig. 16), aper-

ture 171 (Fig. 6), conduit 173, into the pressure regulator chamber 54.

It will be noted in Fig. 3 that the low pressure gears 154 are thicker or wider from face to face than the high pressure gears 183. The low pressure gears 154 are so constructed in order that they may pump up an excess of fuel over that required for the high pressure stage 183, 184. This excess of fuel is delivered into the reservoir 138, whence the high pressure stage takes its 10 supply through the intake 199. The high pressure stage pumps out of the reservoir 138 as much liquid fuel as it needs, the level being constantly up to the bottom of the conduit 203 in the sleeve 160, and the excess of liquid fuel from 15 reservoir 138 passes over into by-pass conduit 26, whence it may be piped back to the tank in a two pipe system.

In a one pipe system, the excess liquid fuel from reservoir 138 goes into the by-pass conduit 20 26, the lower end of which is closed by plug 28, and in such a system the plug 24 is removed and excess fuel passes back into the upper strainer chamber, which leads to the intake conduits 143, 141, 195, 194 for the low pressure gears 154, 25 155.

The high pressure stage of the pump also pumps an excess of fuel over that required for the burner, and this excess is by-passed by means of the pressure regulator valve, through the conduits 120, 121, bellows 106, into chamber 55, conduit 63, and by-pass 26. The plates 161-164 30 may be made of cast metal, the apertures and slots therein being cored out, if desired, and later accurately machined, or they may be drilled in 35 later, since they are all round apertures.

The plates are all provided with smooth, machined surfaces, so that when the plates are clamped together they provide fluid-tight engagement between each other. The plate 161 is, 40 of course, slightly thicker than the gears 154, 155, and the plate 163 slightly thicker than the gears 183, 184. The shaft 156 in this embodiment may be of the same size throughout its length, being merely provided with a flattened 45 portion 204 at the end for attachment to the source of motive power. At its inner end, shaft 156 is provided with a transverse slot 205, opening out into the end of the shaft for receiving a 50 key 206.

The key 206 may be a flat plate, having rectangular sides of slightly greater length than the diameter of the shaft 156, with its ends engaged in slots 207 formed in the bores of gears 183, 55 184, and 154.

These slots are similar to that shown in dotted lines in Fig. 11 with respect to a different gear. The same sort of slots are formed in the ends of the stub shaft 190, and keys are provided for 60 securing gears 183 and 154 to rotate with stub shaft 190. The gear 155 is mounted on shaft 156 for free rotation on that shaft. Thus it will be observed that the gears are arranged in a single train, driven from the shaft 156 as follows: 65 Shaft 156 drives gear 184 through the key and slot connection. Gear 184 drives gear 183. Gear 183 drives stub shaft 190, which drives gear 154. Gear 154 drives gear 155. Of course, all of these gears are rotating at the same speed, but by 70 means of such a single train drive all of the backlash is taken up through the gears, thereby reducing noise. Since the shaft 156 is all of the same size and it may be freely drawn from the gear 184 and key 206, it is possible to arrange the 75

shaft 156 so that it may very easily be withdrawn to permit inspection of the shaft seal and other details.

The assembly of the elements of the fuel unit 5 as shown in Fig. 3 is for a pump having right hand rotation, as shown by the arrow, Fig. 3, looking at the right or shaft end or rear end of the fuel unit with the valve on the right and the strainer on the left. Certain manufacturers may 10 prefer to have the pump arranged for left hand rotation. This can be accomplished by a re-assembly of the parts so that the regulator valve is on the left of Fig. 2 and the strainer on the right of Fig. 2, the plates 161-164 being so assembled 15 that the apertures therein combine with the apertures formed in the main casting 23, providing suitable intake and output conduits for the pump stages and the suitable communication with the by-pass and with the burner outlet, 20 as previously described.

When it is desired to arrange the unit element for a left hand rotation, with the valve on the right, referring to the rear end, or for a right hand rotation, with the valve on the left, referring to 25 the rear end, then the idler gears 183, 184 must become drivers, and the gears 184, 185 become idlers and disposed below the drivers, as shown in Fig. 8. This makes the liquid delivery from the teeth toward the holes in the plate 162. The 30 reason for changing the gears is that the helical teeth may slope in such direction as to force the liquid.

The main casting could be provided with such 35 suitable apertures that the manufacturer could make this assembly in any manner desired, any unnecessary apertures being plugged up, but the preferred mode of handling the matter is that the manufacturer of the oil burner specify which 40 of the four conditions as to rotation or location of the valve are desired. Then, with the same castings, the present fuel units can be supplied in any of the forms desired by merely providing suitable conduits. For example, in Fig. 8 the 45 location of the shaft 156 is the same as in Fig. 3, but the plates 162 to 164 have been swung about this axis or merely lowered to a lower position in the reservoir housing 132. Plate 161 is always 50 merely lowered (never reversed), so that the hole in the plate and the tube 160 are always at the top of the plates. The reason for this is that the reservoir overflow should always be higher than pressure pump intake, so that sufficient liquid will be retained to prime the pressure gears.

The bore 158 for the alignment of tube 160 is 55 located above the shaft 156 at the same distance from the shaft as pin 159 is below the shaft in Fig. 3. The bore 157 for the pin 159 is located below the shaft 156 at the same distance from the shaft 156 as tube 160 is above the shaft 156 60 in Fig. 3. The plates 161-164 are so arranged that their apertures and slots provide the conduits previously described to make the pump operate in the same way, except that it may now be arranged for left hand rotation with the valve 65 on the right, or for right hand rotation with the valve on the left.

Referring now to Figs. 10 and 11, these are 70 views which show that some of the same elements may be utilized to provide a single stage pump having the same by-pass feature, the pump providing an excess of fuel over that required by the burner. In this case the features of the strainer and regulator valve will be identical with that previously described.

75 The intake of the pump gears 208, 209, which

may be identical in construction to the gears 183, 184, is from the upper strainer chamber 55a through the same conduits 148, 143, 141. The outlet from the pump gears 208, 209 is always on the opposite side of the gears, and leads to 5 the regulator valve chamber 54 through conduits similar to the conduits 171, 173.

The main casting 210 for such a single stage unit (Fig. 10) is similar in construction to that of the casting 23 in that it has the same strainer 10 housing 24, regulator valve housing 25, and by-pass conduit 26. The by-pass conduit 26 communicates with the upper chamber 55a of the strainer housing, as shown in Fig. 2, through the same aperture 62 and with the upper chamber 15 55 of the regulator valve through the same threaded aperture 63. Thus, in a single stage pump the pump is again arranged to take liquid from the fuel strainer and to discharge liquid fuel under pressure into the regulator valve housing, 20 and any excess of fuel which is by-passed by the regulator valve passes back into the by-pass conduit 26 through the port 63. A plug 28 may be removed and a return conduit used back to the tank or the plug 64 may be removed (Fig. 2) 25 and a single pipe system used, by permitting the excess to flow back from the by-pass conduit 26 through port 62 into the strainer housing 55a.

In each case the drive shaft 156 or 211 may be 30 similar in construction, and it is rotatably supported by a cast iron bearing 212, which is pressed into a bore 213 in the face of the casting. The single stage castings 210 are made in two forms; that is, the form shown in Figs. 11 and 18, having a circular face 214 adjacent the top of one 35 side of the casting, and the other form shown in Figs. 17 and 19, having the circular face 214 located on the lower part of the side of the casting.

In the embodiment of Figs. 11 and 18, it will be 40 seen that the drive shaft 211 is located below the stub or idler shaft 215.

In the embodiments of Figs. 17 and 19 the idler shaft 215 is located below the drive shaft 211. By the use of two castings of these types, pump 45 units may be manufactured meeting all four requirements of oil burner manufacturers, that is, pump units may be made with a right hand rotation of the shaft or a left hand rotation, and either of these types may be made with the 50 strainer on the right or the strainer on the left. The additional variations in the units to accomplish this result are merely brought about by drilling the conduits from the strainer to the pump and from the pump to the regulator valve 55 in a different manner. For example, in Fig. 11 the conduit 216 leads from the upper part of the strainer housing to the intake side of the gears 208, 209. The conduit 217 leads from the output side of the gears 208, 209 to the lower part 60 of the regulator valve housing.

Each of these two conduits preferably 65 communicates with a diagonal slot 218, 219, arranged in the circular face 214 at the edges of the teeth of the gears, on the intake side and output side of the gears, respectively.

In Fig. 17 the conduit 220 leads from the upper part of the strainer chamber to the input 70 side of the gears, and the conduit 221 leads from the output side of the gears to the regulator valve chamber 54.

It will be observed that the slots 222, 224 in the face 214 are arranged diagonally in order to prevent interference of these slots with the aper- 75

tures for the securing bolts 225'. The same is true of the slots in Figs. 11, 18 and 19.

Referring to Fig. 18, 225 indicates the conduit from the strainer to the pump intake, and 226 indicates the conduit from the output of the pump to the pressure regulator valve.

In Fig. 19, 227 indicates the conduit from the strainer to the intake of the pump, and 228 indicates the conduit from the output of the pump to the regulator valve.

Figs. 21, 22 and 23 are horizontal sectional views taken on the plane of these conduits and showing the course of the conduits as described.

Referring now to Fig. 10, the face 214 of each casting is provided with a bearing aperture 229 for receiving and rotatably supporting the end of the idler shaft 215. The face is also provided with apertures 230 and 231 for receiving the alignment pins 232 and 233. A gear housing plate 234 has suitable apertures registering with the apertures 230 and 231 for receiving the alignment pins 232, 233. It also has the two intersecting gearing bores 235, 236 adapted to support and house the gears 208, 209 as described with respect to the gears in the two stage pump.

The gear housing plate also is provided with suitable apertures 237 for the securing bolts 225', which are threaded into bores in the face 214 of the casting, and which also pass through the cover plate 238.

In the case of the two stage pump or any pump which is surrounded by a reservoir 138, as in Fig. 3, a slight leakage is immaterial, as it will only leak out from between the plates 161-164 into the reservoir 138. Therefore, no gaskets are necessary between those plates.

In the case of a single stage pump of the type shown in Fig. 10, the plate 234 is preferably formed with suitable grooves 239, 240 for receiving a compressible gasket to effect a water-tight joint between this plate, the housing casting 210, and the plate 238.

The plate 234 is shown in elevation in Fig. 11, and it will be apparent that the grooves 239-240 are spaced from but surround the bores 235, 236 which receive the gears 208, 209.

It will thus be observed that the present pump may be embodied in the unit as a two stage or a single stage pump, and in each case the same type of casting may be used with slightly different machining and slight modification and to make a unit meeting all of the four requirements of oil burner manufacturers.

Referring now to Figs. 3 and 10, the main casting 23 or 210 is provided with a tubular extension 241, serving to support the bearing 242 for the shaft 156, and a liquid-tight seal, indicated in its entirety by the numeral 243.

The bearing supporting member 241 is provided with an internal bore 244, the outer end of which is threaded to receive a threaded reservoir body 245, which carries the bearing 242. The reservoir body 245 comprises a cylindrical body having a through bore 246 and having a reservoir 247 formed therein, and communicating with the bore 246, but closed by the wall of the bearing 242, which has a tight frictional fit in the bore 246.

The bearing 242 may consist of a porous metal bearing adapted to conduct lubricant from the reservoir 247, where it is held by a filling of waste or wicking 248. The reservoir body 245 has an outer, non-circular hub 249. The bore 244 terminates at an annular shoulder 250, but communicates with a counterbore 251, leading into the by-pass conduit 26.

The seal 243 may be provided with a guide tube 252 adapted to be received in the bore 244, and held therein by engagement with the annular shoulder 250, and with an annular end of the reservoir body 245. The right end of the sleeve 252 is turned down at 253 to form a groove which communicates with an aperture 254 located at the bottom of the sleeve and in registry with a bore 255 through the bearing supporting body 241.

The purpose of the apertures 254, 255 is to permit any leakage which might leak past the seal 243 to leak directly out of the body 241 and indicate leakage of fuel oil from the seal, as distinguished from leakage along the shaft 156, which might result from the bearing reservoir 247. Thus any fuel leakage is immediately indicated and distinguished from that coming from the self-lubricating bearing.

The member 256 is a tubular shield surrounding the shaft 156 beyond the bellows, and is intended to protect the bellows from the wash of fuel oil; but it may be eliminated. The bellows 257 has one end attached to an annular supporting ring 258, which is clamped between the sleeve 252 and the shoulder 250. Its opposite end is secured on a sliding end wall 259 and has a fluid-tight connection with the end wall 259.

End wall 259 comprises a steel member provided with a bore 260 for passing shaft 156, and with a flat annular surface 261 for engaging a complementary surface in the form of a rib 262 on a collar 263. Collar 263 has a tight frictional fit on the shaft 156 and rotates with the shaft. It is spaced from the end of bearing 242 by a hardened and ground steel washer 264, which takes the thrust imposed by the spring 265.

The fluid-tight seal about the shaft 156 takes place at the surfaces 243, 262, which are lapped to provide a fit as nearly perfect as possible; and these surfaces are held in contact by the spring 265, which surrounds the shaft 156, but does not engage the shaft.

Spring 265 engages the bearing 212 at one end, the bearing being shorter than its bore by a small amount. This is one way to provide a recess for the spring 265. The other end of the spring fits in a recess in the end wall 259, and consequently the end wall 259 of the seal is urged toward the right.

The edge 266 of the end wall has a cylindrical surface, which has a sliding fit inside the sleeve 252, thereby guiding the end wall 259 at its outer edge, and permitting freedom of end wall 259 with respect to shaft 156.

Such a bellows type seal has a minimum amount of friction, yet there is a fluid-tight seal about the rotating shaft which prevents any leakage along the shaft. The shaft has the high pressure gears at its inner and closed end, and next to the high pressure gears are located the low pressure gears, while the chamber to be sealed is actually only in communication with the by-pass conduit 26 so that there is a very low pressure acting against the seal, comprising merely the amount of head necessary to force the liquid back to the tank.

It will thus be observed that I have invented an improved fuel supply unit for oil burners, which is adapted to fulfill all of the four requirements of oil burner manufacturers. With very little change, the unit can be made for right hand rotation or left hand rotation, with either the strainer on the right or the strainer on the left. It may be embodied in a one pipe system or a two pipe system, by merely making a slight change, and

may be used in the form of a single stage pump or a two stage pump.

The present arrangement is flexible and adaptable to all conditions with a minimum amount of patterns and castings, and therefore the unit may be constructed at a very low cost, placing it within the reach of a larger number of manufacturers of oil burners.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

A liquid fuel pump adapted to be assembled differently for rotation in either direction, comprising a metal base member having a plane face for supporting a pump assembly, said member having a shaft bearing, a drive shaft in said bearing, a pair of metal posts mounted in apertures 25 of said base member and projecting from said

face, a first gear housing plate, a bearing plate, and a second gear housing plate carried by said posts, a cover plate and means for securing said plates to said base member, a reservoir surrounding all of said plates, said base member having a pair of pump conduits at each side of said shaft, each of said gear housing plates having communicating cylinder bores for housing two intermeshing gears, and one of said housing plates having apertures forming continuations of said conduits, 10 said bearing plate having bearings for said drive shaft and a stub shaft, pairs of gears in said bores on said shafts, one pair being larger than the other, said bearing plate having on each side thereof a slot extending from the edge of said bearing plate, to one side of each pair of the meshing gears, and said bearing plate having on each side a three branch slot, each three branch slot having one branch extending to the other side of each pair of the meshing gears, and having branches extending into registry with the pump conduits from said base member, whereby said bearing plate may be inverted to adapt the pump for rotation in either direction.

HERBERT C. OSBORNE. 25
